D. J. GOLDEN

ATHLETIC SHOE

Filed May 22, 1924

Inventor:
Daniel J. Golden.
by Wright Brown Quincy May

UNITED STATES PATENT OFFICE.

DANIEL J. GOLDEN, OF BROCKTON, MASSACHUSETTS.

ATHLETIC SHOE.

Application filed May 22, 1924. Serial No. 715,093.

To all whom it may concern:

Be it known that I, DANIEL J. GOLDEN, citizen of the United States, residing at Brockton, in the county of Plymouth and 5 State of Massachusetts, have invented new and useful Improvements in Athletic Shoes, of which the following is a specification.

This invention relates to a shoe having ground-engaging cleats projecting from the 10 tread face of the outer sole. The object of the invention is to provide improved means for connecting the cleats with the outer sole in such manner as to stably support the cleats and prevent them from tipping without 15 interfering with the flexibility of the sole, the nature of the connecting means being such that the cleats may be readily detached from the sole, and are free from liability of being accidentally detached. 20 This object is attained by the improved construction hereinafter described and claimed.

Of the accompanying drawings forming a part of this specification,—

Figure 1 is a bottom view of a portion of 25 a shoe as it appears before the cleats are connected with the outsole.

Figure 2 is a view similar to Figure 1 showing the cleats connected with the outsole.

Figure 3 is a section on line 3—3 of Figure 2.

Figure 4 is an enlarged sectional view showing one of the cleats.

Figure 5 is an enlarged sectional view 35 showing a portion of the outsole.

Figure 6 is a section on line 6—6 of Figure 4.

Figure 7 is an enlargement of a portion of Figure 3.

Figure 8 is an enlarged sectional view showing a modification.

Figure 9 is a view similar to Figure 5, showing a modification.

The same reference characters indicate the 45 same parts in all of the figures.

The outsole 12 of an athletic shoe is provided with a plurality of orifices 13 extending through the sole from side to side. In the orifices are inserted metal sockets or 50 bushings 14 which are internally screw-threaded, and are provided with annular flanges or heads 15 seated on the tread face of the sole. The flanges are united to the sole by fastenings, such as rivets 16 extend-

ing through the flanges and sole, as shown 55 by Figure 5.

The cleats 17 may be of any desired external form, and are here shown as truncated pyramids. Each cleat has an enlarged base face 18 and is provided with a 60 shank having a screw threaded portion projecting from the base face and adapted to engage a socket 14, as shown by Figure 7.

The cleats are preferably of molded vulcanized fiber or other moldable and somewhat compressible material, each cleat being preferably molded upon its shank and interlocked therewith so that the cleat cannot turn on the shank. The preferred form of the shank is that shown by Figures 4 and 65 70 6, the shank including a major portion 19 having a head 20 and ears 21 all embedded in the cleat, and a screw threaded minor portion 22 projecting from the base face 18.

The cleat is adapted to be manually turned 75 to screw the shank portion 22 into a socket 14. This operation is continued until the base face of the cleat is firmly seated on the flange 15 of a socket, the compressibility of the material of the cleat permitting the base 80 face 18 to conform closely to the flange 15 and to the heads of the rivets 16, and be indented by said heads, so that the cleat and its shank are free from liability to be accidentally turned in a direction unscrewing 85 the shank from the socket.

I prefer to impart a concave form to the base face 18 as shown by Figure 4. The intersection of the concave face with the side faces of the cleat forms an acute angled 90 margin 24 adapted, by the compressibility of the cleat material, to be somewhat distorted as shown by Figure 7, and frictionally engage the surface on which the cleat is seated and thus additionally oppose the accidental turning of the cleat.

The flanges 15 and their fastenings 16 impart rigidity to the portions of the sole covered by the flanges, so that the cleats are stably supported on the sole. The flexibility 100 of the sole is practically unimpaired by the flanges because they are independent of each other and are spaced apart.

In case the cleat is made of lifts of sole leather as indicated by Figure 8, the shank 105 may be separable from the cleat and may include a major portion 25 inserted in an orifice formed for its reception in the cleat,

a head 26 seated on the outer end of the cleat and adapted to be engaged by a screw driver, and a threaded portion 27 projecting from the base face 18 and adapted to engage 5 a socket 14.

If desired, the flange 15 may be seated on the inner face of the sole as shown by Figure 9, although I prefer to seat the flanges on the tread face.

10 I claim:

An athletic shoe having orifices extending through its outsole, internally threaded metal sockets inserted in said orifices and provided with annular flanges of greater

15 diameter than the sockets and seated on a face of the sole around the sockets, rivets uniting the flanges in the sole and thereby

securing the sockets in the sole, said rivets having heads projecting outward from the tread face and from the flanges, and cleats 20 of moldable compressible material having enlarged concave base faces formed to extend throughout the area of the socket flanges and cover the projecting heads of the rivets and adapted to be indented by said 25 heads, the cleats being provided with screw threaded shanks projecting from said concave faces, and engaged with the sockets, to press the base faces of the cleats into non-rotating engagement with the projecting 30 heads of the rivets.

In testimony whereof I have affixed my signature.

DANIEL J. GOLDEN.
